Design No. 19,154, dated June 11, 1889.

UNITED STATES PATENT OFFICE.

VICTOR HENRY ROTHSCHILD, OF NEW YORK, N. Y.

DESIGN FOR A SHIRT-BOSOM.

SPECIFICATION forming part of Design No. 19,154, dated June 11, 1889.

Application filed May 13, 1889. Serial No. 310,647. Term of patent 3½ years.

To all whom it may concern:

Be it known that I, VICTOR HENRY ROTHSCHILD, in the city, county, and State of New York, have invented and produced a new 5 and original Design for Ornamenting Shirt-Bosoms and Garments, of which the following is a full, clear, and exact specification.

The accompanying illustration represents a plan view of a shirt ornamented with my 10 design.

The design consists of a knot-like figure A, parallel cord-like lines B, drawn at each end of the said knot-like figure, having the appearance of being a portion thereof, three ring-like figures C, which appear at the outer 15 end of each of the cord-like figures, representing in combined outline a clover-leaf, and a circular figure D between the said ring-like figures drawn in imitation of a button.

I claim—

20 A design for ornamenting shirt-bosoms and garments, substantially as herein shown and described.

VICTOR HENRY ROTHSCHILD.
